UNITED STATES PATENT OFFICE.

CALVIN F. HALL, OF ATHENS, ILLINOIS.

JOIST OR BEAM SUPPORT OR ANCHOR.

1,229,070.

Specification of Letters Patent.

Patented June 5, 1917.

Application filed July 8, 1916. Serial No. 108,161.

To all whom it may concern:

Be it known that I, CALVIN F. HALL, a natural born citizen of the United States, residing at Athens, in the county of Menard, and State of Illinois, have invented certain useful Improvements in Joist or Beam Supports or Anchors, of which the following is a specification, reference being had therein to the accompanying drawing.

10 This invention relates to improvements in joist or beam supports or anchors, one object of the invention being the provision of a metal attachment adapted to be secured to the end of the floor or ceiling joist or beam 15 to engage the masonry wall without necessitating the ends of the joist or beam being embedded therein.

A further object of this invention is the provision of a novel construction of joist anchor which will permit of the laying of the brick in the wall close to such anchor, and at the same time rigidly support the joist to the wall.

In the accompanying drawings:—

25 Fig. 1 is a side elevation of the present device showing one end of the joist and the adjacent portion of a wall.

Fig. 2 is a top plan view thereof.

Fig. 3 is a bottom plan view thereof.

30 Fig. 4 is a detail perspective view of the anchor *per se* in inverted position.

Referring to the drawings, the numeral 5 designates the joist and 6 the masonry wall.

The anchor 7 is made of two joist engaging plates of metal 8 and 9, for attachment to the sides of the joist 5 and each one of which is formed to provide the offset including a right angularly extending joist engaging flange 10 for attachment to the 40 end of the joist by the fastening devices 11 and the wall engaging wing 12. Each wing is provided with the outwardly extending wall engaging lip 13 arranged in the plane of the upper edge of the flange 10 and flush 45 with the side face of the adjacent plate. A

downwardly extending wall engaging lug 14 is formed on the outer end edge of each wing and is arranged in spaced parallel relation to the adjacent flange end. The extreme edge of each wing lies in substantial alignment with the lugs and is inclined downwardly as at 15.

When the present device is assembled, the right angled wings lie flush together, and are adapted to fit within the space between two or more bricks, while the bricks occupy the space below the flanges and within the lips, the portion of the wall above being laid upon the flanges.

In this way metal plates are anchored in the wall, and as the thickness of the metal employed is such as to permit of their introduction between the layers of bricks, it is apparent that an exceedingly strong anchorage is provided.

It is also apparent that with an anchorage of this type, the end of the joist is protected from dampness from the wall.

What I claim as new is:—

A joist anchor including a pair of joist 70 engaging plates adapted for engagement with the sides of the joist adjacent one end, a joist engaging flange on the end of each plate and adapted for engagement with the end of the joist, and wall engaging wings 75 projecting at right angles from the outer end of each flange and arranged in close parallel relation with each other, a wall engaging lip extending from the upper edge of each wing and arranged in the plane of 80 the upper edge of the plates and flanges and terminating flush with the outer side faces of the adjacent plates, and an anchoring lug extending downwardly at right angles from the outer end edge of each lip and arranged 85 in spaced parallel relation with the adjacent flanges.

In testimony whereof I affix my signature.

CALVIN F. HALL.
